LEVER-FASTENING FOR BANDS

Gilbert Thomas Walker, Birmingham, England

Application December 3, 1936, Serial No. 113,947
In Great Britain January 18, 1936

3 Claims. (Cl. 24—191)

This invention relates to lever-buckles or lever-fastenings for bands, straps and the like, such, for example, as are used in connection with stocking suspender bands, truss bands, brace webbing and the like, to enable the effective length of the band or webbing to be adjusted according to requirements, the band or webbing being adapted to be held in the position desired by means of the lever.

10 The object of the present invention is to provide a lever-buckle or lever-fastening of an improved and simplified construction having means whereby the adjustment of the band or webbing is considerably facilitated.

15 Figure 1 of the accompanying drawing represents a front view of a lever-buckle or lever fastening constructed in accordance with this invention, showing it applied to the band or webbing.

20 Figure 2 is a rear view of the lever-buckle or fastening with the return-end of the band or webbing in section.

Figure 3 is a side view of the fitting with the lever in its turned-down or clamping position.

25 Figure 4 represents a front view of the lever-fastening without the band or webbing, the lever being in its raised position; showing the lower hinged gripping bar which is provided, the said gripping bar being turned forwardly.

30 Figure 5 illustrates a cross-section on the line 5—5, Figure 4, showing the fitting applied to the band.

Figure 6 represents a similar cross-section but with the lower gripping bar turned back, and the lever in its turned-down position.

35 Figure 7 is a cross-section on the line 7—7, Figure 4, with the fitting applied to the band.

Figure 8 is a cross-section similar to that shown in Figure 7, but showing how the lower gripping bar is turned back by the pull on the band.

40 Figure 9 is a front view of a modified form of lever-fastening.

Figure 10 shows a further modified arrangement.

Figure 11 represents a vertical section on the line 11—11, Figure 10.

Figure 12 is a front view showing a third modification of the invention.

45 Figure 13 is a front view showing a fourth modification of the invention.

Referring to Figures 1 to 8 of the drawing, the improved lever-buckle or lever-fastening comprises a rectangular metal frame support 1 formed from a single length of circular-sectioned wire, the upper portion of the frame being bent forwardly, as shown. The opposite ends of the frame are inwardly offset near the middle at 2, and connecting together the said inwardly-cranned portions of the frame is a fixed cross-

5 bar 3 to which is connected a gripping bar or narrow gripping plate 4 for co-operating with the lever member 6 of the fitting by gripping the band thereagainst. The said lever member is hingedly mounted upon the top bar 1m of the frame 1 and is formed from a single sheet metal blank shaped or bent up to provide two front gripping parts 8 with toothed lower edges 17 and set upon opposite sides of a forwardly-bent middle part constituting a finger-piece 9 for turning the lever angularly about the top bar of the frame. The lever 6 is pivoted to the said top bar by curled-over rear edges disposed immediately behind the front gripping parts 8, and constituting hinge sleeves 10, whilst disposed between these hinge sleeves is a broad integral tongue portion 12 which is directed first rearwardly and substantially horizontally (assuming the lever to be in its operative or turned-down position) and then downwards and forwardly, 10 the tongue, which is thus given a rounded hook shape, lying at the rear of the front gripping parts 8 of the lever and partly behind the toothed edge portions 17 of the gripping bar or plate 4 when the lever is in its clamping position, as 15 shown in Figure 6.

20 The gripping bar or plate 4 is disposed below the lever 6, but instead of the said bar or plate 4 being fixed to the frame it is hingedly connected to the fixed cross-bar 3, the lower edge of the gripping bar or plate 4 being curled into a sleeve 4a to surround the said fixed cross-bar. The opposite ends of the hinged gripping bar 4 are provided with lateral projecting lugs, stops or extensions 13 which project beyond the ends of 25 the frame 1 and constitute stops, as well as means for enabling the gripping bar 4 to be moved angularly by hand when desired. These lugs or stops 13 by engaging the frame 1 limit the angular movement of the gripping bar 4, the 30 latter when in its normal position lying in a substantially vertical plane, as shown in Figures 6 and 8, the arrangement being such that it may be moved forwardly about its lower edge into the position shown in Figure 7, leaving a wide 35 gap or clearance between its upper edge 8 and the lever for the passage of the main part of the band or webbing 14, which may be a truss band, suspender band or the like. The return-end of the band 14 is attached to the lower bar 1a of the frame, the gripping bar 4 being spaced from the said lower bar of the frame by a slot or clearance 15. The gripping bar 4 is limited in its forward movement by the bent-up middle part or stop 3a of the bar 3 upon which it is 40 mounted. This limiting is effected by engagement of the bar 4, as it rotates on the bar 3, with this bent up part. The middle portion of the top edge of the angularly-movable gripping bar 4 is formed with a forwardly-bent toothed 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570

part 16 disposed opposite or below the rolled-over middle part 12 of the lever, whilst disposed at the top edge of the gripping bar 4, at each end of the forwardly-directed toothed middle 5 part 16, is a pair of large projecting prongs or sprags 17 and 18 set in different planes, as shown in Figures 7 and 8, the prongs or sprags lying close to the hinge-sleeves 10 at the ends of the lever 6 when the gripping bar is turned back 10 into the plane of the frame.

The object of hingedly mounting the gripping bar 4 and providing it with the prongs or sprags 17 and 18 at opposite ends in the above manner is to enable the band or webbing 14 to be temporarily held after adjustment, prior to the turning down of the lever 6. To adjust the band or webbing, the gripping bar 4 is turned forwardly by the projecting lugs 13 at opposite ends, which may be held between the finger and thumb, leaving a 20 wide clearance or aperture between the bar 4 and the lever 6, said lever having been first moved into its inoperative position. The band or webbing 14 may now be pulled down through the aperture. The said band, however, engages against the 25 prongs 17 and 18 of the gripping bar 4 and any pull on the band in a direction which tends to loosen the latter, that is in an upward direction, causes the gripping bar 4 to be moved angularly rearwards (unless the same is positively held in its forward position) and the band is then engaged successively by the prongs 17 and 18 and is gripped between the said prongs and the hinge sleeves 10 of the lever, the band being consequently held in its adjusted position, although the lever 6 is not 30 turned down. When the lever is finally turned down the band 14 is also held between the front gripping parts 8 of the lever and the forwardly-set toothed middle part 16 of the gripping bar, the curled-over tongue 9 of the lever 6 pressing the band rearwardly over the said middle part of the gripping bar. The band or webbing 14 is thus 35 securely held or clamped in an efficient manner. Although the prongs or sprags 17 and 18 on the gripping bar 4 effectively prevent the band or webbing from slipping out of its adjusted position prior to the turning down of the lever 6, the said band or webbing may be easily slackened and moved between the lever and the gripping bar, when desired, if the latter is held by hand in its forward position by means of the projecting lugs 13 at its opposite ends.

The arrangement illustrated in Figure 9 of the drawing is substantially the same as the above described, the frame being shown at 1a but the 55 top edge of the hinged gripping bar 4a, is provided with a forwardly-bent middle part 16a, with a straight edge 6m, for co-operating with the lever 6a to hold the band or webbing in its fastened position, whilst at each end of the gripping bar 4a is a pair of forwardly-directed teeth 18a, with an upstanding tooth 17a, shaped as shown, at each side of the straight-edged middle portion 16a. The teeth 17a and 18a engage with the band, so that a pull on the latter turns the bar into 60 line with the frame 1a and thus temporarily holds the band against the hinge-sleeves 10a of the lever prior to the latter being turned down into its clamping position.

In the construction shown in Figures 10 and 11 70 the frame is indicated at 1b and, the end extensions, or stops 13b of the hinged gripping bar 4b are curved, as shown, the bar having a set of forwardly-directed teeth 16b at the middle and up-standing teeth or sprags 17b and 18b adjacent

each end, the teeth 18b being carried by the curved end extensions or stops 13b of the gripping bar and being shaped as shown.

If desired, the lever, here shown at 6c may have a curled-over or hook-shaped rear part 12c formed 5 with a series of horizontal scorings, or ribs 19c disposed preferably parallel to one another, as shown in Figure 12 the ribs or grooves enabling a better grip to be obtained between the said curled-over part 12c and the band, so that a pull 10 on the latter is more effective in turning the lever more closely into its gripping position. Or the curled-over or hook-shaped rear part 12c of the lever 6c may be corrugated or roughened in any suitable manner, so as to provide a good grip 15 surface. It may, for example, be formed, as shown in Figure 13, with a series of small projections 20c extending over a portion of its area, or over its entire outer surface. The curled-over part may be bent to any suitable cross-sectional 20 shape.

Having fully described by invention, what I desire to claim and secure by Letters Patent is:—

1. The lever-fastening for bands comprising a frame, a band-engaging lever on the frame, 25 hinge-sleeves at opposite sides of the lever, a hinged bar on the frame below the lever and constructed and arranged to cooperate with the hinge-sleeves to hold the band when the lever is in an unfastened position, band-engaging sprags at each end of the hinged bar disposed below the hinge-sleeves in different planes, and a forwardly-directed gripping edge on the hinged bar separating the sprags at opposite ends of the latter. 35

2. A lever-fastening for bands comprising a frame having top and bottom bars, an intermediate bar carried by the ends of the frame, a lever on the top bar of the frame, a curled-over rearwardly extending part on the lever, a front finger-piece on the lever, a toothed band-engaging part on the lever on either side of the front finger-piece, a gripping member hinged on the intermediate bar of the frame, stops on the frame and hinged gripping member for limiting the angular movement of the latter in directions towards and away from the frame, sprags disposed in different planes at each end of the hinged gripping member for co-operating with the lever to hold the band when the lever is in an unfastened position, and a forwardly-directed part 40 separating the sprags at the two ends adapted to engage and hold the band when the lever is in a fastened position. 45

3. A lever fastening for bands, comprising a frame having top and bottom bars, an intermediate bar on the frame, a lever on the top bar of the frame, a curled-lever rearwardly-extending part on the lever, a hinge-sleeve on each side of the rearwardly-extending part of the lever, a finger-piece at the front of the lever, a front toothed part on either side of the finger-piece, a gripping member hinged on the intermediate bar of the frame, stops on the frame and hinged gripping member for limiting the angular movement of the latter in opposite directions in relation to the frame, sprags disposed in different planes at each end of the hinged gripping member adapted to co-operate with the hinge-sleeves of the lever to hold the band when the lever is in its unfastened position, and a forwardly-directed part separating the sprags for engaging and holding the band when the lever is in its fastened position. 65 70
